(57) **CLAIM**

I claim the ornamental design for a shoe sole, as shown and described.

DESCRIPTION

FIG. 1 is a front perspective view of the shoe sole showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof with environmental unclaimed subject matter; and,

FIG. 9 is a top perspective view thereof with environmental unclaimed subject matter.

The broken lines in the drawing represent environmental structure in the form of a shoe upper showing the shoe sole in a condition of use, as well as portions of the shoe sole that are not claimed. The broken lines and structure they depict form no part of the claimed design.
